2 SHEETS—SHEET 2.

UNITED STATES PATENT OFFICE.

EMIL ANDERSON, OF NEW YORK, N. Y., ASSIGNOR TO ANDERSON GAS TURBINE COMPANY, OF NEWARK, NEW JERSEY, A CORPORATION OF NEW JERSEY.

COMPRESSOR.

1,105,479.

Specification of Letters Patent. Patented July 28, 1914.

Original application filed January 5, 1912, Serial No. 669,690. Divided and this application filed April 15, 1912. Serial No. 690,736.

To all whom it may concern:

Be it known that I, EMIL ANDERSON, a citizen of the United States of America, and a resident of New York, county and State of New York, have invented certain new and useful Improvements in Compressors, of which the following is a specification, reference being had to the accompanying drawings, forming a part thereof.

10 This invention relates to an improvement in compressors and is a division of my application Serial No. 669,690, filed January 5, 1912.

15 The object of the invention is to simplify and improve the construction and mode of operation of compressors.

20 I will describe my invention in the following specification and point out the novel features thereof in the appended claims.

25 In the accompanying drawings: Figure 1 is a sectional elevation of the compressor connected to a turbine. Fig. 2 is a horizontal section taken on the line 2—2 in Fig. 1. Fig. 3 is a fragmentary side elevation of an 30 adjusting mechanism which forms a part of the apparatus.

As illustrated in the drawings the compressor is operatively connected to a turbine, although it is to be understood that it 35 may be operated from any other suitable source of power. The turbine itself is fully described and claimed in my application above identified. It may be briefly described as follows: It comprises a stationary 40 casing 10 having a cylindrical chamber 12 in its upper portion which constitutes the cylinder of the turbine and contains the rotor 14. The rotor is mounted upon a hollow vertical shaft 16 journaled in suitable bearings 17—18 in the upper and lower ends respectively of the casing, said rotor being provided with blades or reaction surfaces 20 between which the motive fluid is introduced. A series of impeller blades 22 are 45 mounted upon the shaft 16, and these rotate within the water contained in the casing 16 and force it into the lower end of the shaft 16 through which it flows and is discharged from ports 23 into a chamber 24. This

chamber communicates with the spaces between the blades 20 by means of ports 26—27. An exhaust passage 28 is provided which is in communication with the cylinder 12, and a radiating coil 30 may also be provided, which communicates at its lower 55 end with the bottom of the casing 10, and at its upper end with the bottom of the cylinder 12, the coil being provided with the usual cooling ribs or fins 31.

The compressor comprises a cylinder 40 60 within which a piston 41 is slidable, said piston being mounted on a shaft 42 so that the latter is rotatable with respect to the former. The cylinder 40 is provided with an inlet port 44 controlled by a spring-pressed valve 45, and with a discharge port 46 controlled by a spring-pressed valve 47. The inlet port 44 communicates with a pipe 48 through which air or other fluids may be drawn, and the discharge port 46 is 70 connected by a pipe 50 with a receiver 51.

The horizontal shaft 42 is journaled in suitable bearings 54—55 on the end walls of the casing 10, and passes through guides 56 which project inwardly from the casing 75 10. These guides hold a worm wheel 58 against endwise movement on the shaft 42 which, as will presently appear, is arranged to move longitudinally, the worm wheel being loosely splined upon said shaft and 80 meshing with a worm 60 fast on the vertical shaft 16. Mounted on the end of the shaft 42, opposite to the end upon which the piston 41 is mounted, is a propeller 62. This propeller driven by the engine and the end 85 thrust it produces on the shaft, is utilized to actuate the compressor, but it should be understood that other means for producing this result may be employed without departing from my invention.

Affixed to the shaft 42 is a worm 64 which meshes with a worm wheel 65 affixed to a shaft 66 which is journaled in bearings 67—68 on the casing 10. Mounted to rotate with the shaft 66 is a star wheel 69, the fingers of which are adapted to engage the upper end of a tripping arm or lever 70 fulcrumed on a shaft 72 which is slidable in

a slot 73 which is substantially parallel with the shaft 42. The arm 70 is provided with a pair of lugs 74—75 which straddle the shaft 42 in the path of travel of the worm 64. A spring 76 normally holds the arm 70 in engagement with a lug 78 on a bar 79 mounted on the shaft 72. The bar 79 is provided with a reduced end 80 which is slidable in a lug 82 projecting upward from the bottom of the casing 10. The bar 79 is so arranged that its position may be manually changed by means of a finger 84 on a shaft 85, said finger engaging pins 86 on said bar. A hand wheel 88 is provided on the shaft 85 outside of the casing 10, whereby the shaft may be rotated to adjust the bar 79 and thus vary the position of the lug 78 and the fulcrum 72.

The hand wheel 88 is provided with peripheral notches 89 adapted to receive a locking finger 90 projecting from the side of the casing 10, whereby the hand wheel may be locked against rotation. The lever 70, as will be pointed out, is provided to coact with other parts of the mechanism for the purpose of causing a reciprocatory movement of the shaft 42, and this adjustment of the arm 79 will vary the length or stroke of this reciprocatory movement.

When the shaft 16 is rotated, the worm 60 meshing with the worm wheel 58 causes the propeller shaft 42 to rotate. The star wheel 69 being in engagement with the lever 70 is prevented from rotating and with it the worm wheel 65 on the shaft 66 is held stationary. The rotation of the propeller shaft 42 and the engagement of the worm 64 with the wheel 65 causes the propeller shaft to be moved longitudinally toward the right, thus moving piston 41 to the right and drawing a charge of fluid into cylinder 40. This movement continues until the lugs 74—75 on the arm 76 are engaged by the end of the worm 64. This causes the arm 76 to disengage the star wheel 69, whereupon the end thrust of the propeller causes the shaft 42 to be pushed back toward the left thereby rotating the gear 65 and forcing the piston 41 into the cylinder 40 to compress the charge in the cylinder and force it through the port 46 and pipe 50 to the receiver 51.

While the shaft 42 is moving toward the left the lever 70 is allowed to move back under the action of its spring 76 into the path of movement of the star-wheel 69 so that as soon as the next arm of the latter reaches the end of the lever 70, the rotation of the worm wheel 65 will be arrested and the shaft 42 will move again to the right. This movement will cause the piston 41 to draw a new charge into the cylinder 40 through the port 44.

By the use of this device the compressor, which may be used for any desired purpose,

is automatically driven and when used in conjunction with a propeller or other device which produces an end thrust on a shaft, is driven by power which is usually wasted in thrust-bearings.

What I claim is:

1. The combination of a fluid pump cylinder, a receiver, a piston in said cylinder, a rotary and reciprocatory shaft, connected with said piston, means for producing such an end thrust on the shaft as to force fluid into said receiver, gearing associated with said shaft, whereby the latter is positively moved in one direction and means for releasing the shaft from said gearing whereby the shaft is moved in the opposite direction by said end thrust.

2. The combination with a receiver, of a fluid pump cylinder, a piston in said cylinder, a rotary and reciprocatory shaft operatively connected with said piston, a propeller on said rotary and reciprocatory shaft, and means associated with said shaft whereby the said shaft is moved positively in one direction to draw fluid into said pump cylinder and is then released, said shaft being moved in the opposite direction by the end thrust of the propeller to force the fluid into said receiver.

3. The combination of a rotary and reciprocatory shaft, gearing arranged to rotate said shaft and cause it to move longitudinally in one direction, a propeller tending to produce an end thrust in the opposite direction, means operable by the longitudinal movement of said shaft for releasing said gearing to allow the shaft to be moved longitudinally in the opposite direction by the end thrust of the propeller.

4. The combination of a rotary and reciprocatory shaft, a gear loosely splined on said shaft, a worm on said shaft, a second shaft, a worm wheel rotatable with said second shaft, a series of fingers on said second shaft, a lever arranged to be engaged by said fingers to hold said second shaft against rotation whereby when said first mentioned shaft is rotated it is moved longitudinally in one direction, said lever being arranged to be tripped by said first mentioned shaft to free said second shaft, whereby said first mentioned shaft is moved longitudinally in the opposite direction by end thrust.

5. The combination of a cylinder, a piston movable within said cylinder, a shaft rotatably and slidably mounted, said shaft being rotarily connected with said piston, a worm wheel rotatable with said shaft and slidably thereon, a worm on said shaft, a second shaft, a worm wheel rotatable with said second shaft, a star wheel on said second shaft, a lever arranged to be engaged by said star wheel to hold said second shaft against rotation, whereby when said first

mentioned shaft is rotated it is moved longitudinally in one direction, said lever being arranged to be tripped thereby to free said second shaft, whereupon said first shaft is moved longitudinally in the opposite direction by end thrust thereon.

In witness whereof, I have hereunto set

my hand in the presence of two subscribing witnesses.

EMIL ANDERSON.
